(57) **CLAIM**

The ornamental design for an liposuction cannula, as shown and described.

DESCRIPTION

FIG. 1 is a front left side perspective view showing my new design;

FIG. 2 is a front right side perspective view thereof;

FIG. 3 is a top view thereof;

FIG. 4 is a bottom view thereof;

FIG. 5 is a left side view thereof;

FIG. 6 is a right side view thereof;

FIG. 7 is a front side view thereof; and,

FIG. 8 is a back side view thereof.
